UNITED STATES PATENT OFFICE.

ALBERT MORLEY, OF THREE OAKS, MICHIGAN, ASSIGNOR TO THE WARREN FEATHERBONE COMPANY, OF THREE OAKS, MICHIGAN, A CORPORATION OF MICHIGAN.

GARMENT-WEIGHT.

1,110,075.

Specification of Letters Patent.

Patented Sept. 8, 1914.

Application filed April 4, 1914. Serial No. 829,462.

To all whom it may concern:

Be it known that I, ALBERT MORLEY, a citizen of the United States, residing at Three Oaks, county of Berrien, and State 5 of Michigan, have invented certain new and useful Improvements in Garment-Weights, of which the following is a specification.

It is customary in many garments to weight the lower edge thereof in order to 10 insure proper hanging and many forms of garment weights have been devised for such purpose. The most common form of garment weight probably consists of a strip of tape to which a plurality of lead weights are 15 secured to the tape at intervals. In garment weights of this general type, however, the weights are constantly breaking from the tape due to the fact that they are only secured to the tape by threads or other inse- 20 cure means and as the lower edge of the garment wears out, the weights will fall through, producing an uneven hang to the garment.

The principal object of my invention, 25 therefore, is to construct a garment weight with a reinforced edge to prevent the breaking of the weight through a fold of the garment and in my preferred construction the reinforced edge is formed by a cord dis- 30 posed beneath the weights and which keeps the weights out of contact with the fold in the garment.

A further novelty in my invention resides 35 in forming this cord of a resilient material whereby the cord will not only perform the functions hereinbefore stated but will also serve to hold the garment in a slightly dis- tended position at the bottom as is desirable in the fashions of today.

40 In the accompanying drawing the figure is a plan view of a short length of my im- proved weighted tape with a part broken away.

Referring now more particularly to the 45 drawing my improved garment weight con-

sists, as a whole, of a single piece of tape 2 having a plurality of lead weights 3 secured thereto at intervals. The tape 2 and the weights thereon are preferably inclosed in a strip of fabric 4 which is doubled upon 50 itself to form a pocket. Interposed between the lead weights and the fold of the fabric 4 is the cord 5. This cord may be the ordinary form of flexible cord but it is prefer- ably composed of a material having a cer- 55 tain degree of resiliency such as a material known in the trade by the name of "feather- bone."

The cord 5 is held in place by the stitching 6 and the free edges of the fabric 4 are 60 joined together by the stitching 7, thereby holding the tape 2 and weights 3 thereon in place.

In attaching my improved garment weight to a garment a sufficient length is ascertained 65 in order to properly weight the garment, whereupon a fold is made upon the bottom of a garment, such as a skirt, and the garment weight placed within said fold with the cord 5 below the weights so that wear 70 at the bottom of the garment will come upon the cord 5 and not upon the fabric 4. Fur- thermore, the fabric in the garment will not be disintegrated so readily with the cord interposed between the lead weights and the 75 garment.

Having now described my invention, I claim:

A garment weight comprising a single piece of material having a plurality of 80 weights secured thereto, a cover inclosing not be disintegrated so readily with the cord interposed between said weights and said covering and disposed at the lower edge of said cover.

ALBERT MORLEY.
